ANTENNA BRACKET

Francis J. Bradt and Cyril A. Rotolo,
Niagara Falls, N. Y.

Application May 2, 1950, Serial No. 159,618

4 Claims. (Cl. 248—43)

1

This invention relates to supporting devices and more particularly to an antenna mast supporting bracket for a television antenna or the like which is adapted to support the antenna adjacent the upper portion of a house or other building.

An object of this invention is to provide a novel supporting bracket for adjustably securing a television antenna or the like to the peak of the roof of a building such as a private home or the like, and which antenna bracket has means formed therewith for clamping engagement directly with the roof and adjacent portions of the building.

A further object of this invention is to provide an antenna bracket having a threadedly adjustable clamping member with an angle plate swivelly mounted thereon for engagement with a building in a secure manner.

Still further objects of the invention reside in the provision of an antenna bracket that is strong, durable, highly efficient in operation, simple in construction and manufacture, capable of being secured to a building with a maximum of ease and convenience, and which bracket is relatively inexpensive.

These, together with the various ancillary objects of the invention which will become apparent as the following description proceeds are attained by this antenna mast supporting bracket, preferred embodiments of which have been illustrated in the accompanying drawings, by way of example only, wherein:

Figure 1 is a perspective view showing the bracket operatively supporting an antenna mast;

Figure 2 is a vertical sectional view of the antenna mast supporting bracket;

Figure 3 is an elevational view of the antenna mast supporting bracket;

Figure 4 is a top plan view of the invention;

Figure 5 is a perspective view of a modified form of the invention which is adapted for use on a house not having a gable; and

Figure 6 is a sectional detail of the antenna bracket as shown in Figure 5.

Briefly, and by way of introduction to the specification, it will be clear that the invention is especially well adapted for use on the peak at either end of a gable roof and that it is characterized, generally construed, by clamp means whereby a television antenna may be attached and supported wholly and directly from the selected peak comprising a rigid support member embodying an elongated vertical leg adapted to be disposed in spaced parallelism in respect to an end of the wall of said building, a horizontal leg joined with said vertical leg and adapted to extend at right angles

2

from said vertical leg and to underlie the overhanging roof peak, horizontally disposed yoke means carried by the upper end of said vertical leg, said yoke means being U-shaped in plan and having a pair of independent spaced parallel arm portions adapted to straddle the ridge of the roof with said ridge projecting through the space between said arm portions, an end thrust and clamping plate, a jack screw swivelly connected with said plate, screw-threaded means operatively and adjustably mounting said jack screw on said horizontal leg, and means mounted on said vertical leg for the attachment thereto of an antenna mast.

15 With continuing reference to the accompanying drawings wherein like reference numerals designate similar parts throughout the various views, reference numeral 10 generally designates a portion of a house having a peaked roof and a suitable gable on which the antenna bracket, generally designated by reference numeral 12, is adapted to be secured to support suitable television antenna or the like as indicated at 14.

The antenna bracket 12 includes a principal 25 supporting member 18 which is of substantially L-shape having a vertically extending leg 20 and an arm 22 extending at substantially right angles to the leg 20.

20 Welded or otherwise secured to the upper portion of the leg 20 is the bight portion of a substantially U-shaped member 24 which has depending therefrom screws 26 for working engagement into the tile, shingle, or other pitch type or equivalent roof forming a part of the building 10.

25 Also welded to the leg 20 are vertically spaced rings 28 and 30 which have fitted therein screws 32 and 34 which, in combination with lock nuts 36 and 38, provide means for securely holding the mast of the antenna 14 in an adjusted position 40 relative thereto.

35 Threadedly engaged in a nut 40, welded to the arm 22, is a threaded jack screw 42 which is provided with a handle 44 at one end. The upper end of the screw 42 is provided with a swivel joint 46 for swivelly or pivotally mounting an angular end thrust plate 48 which when the arms of the U-shaped member 24 are positioned at either side of the fixed roof and when the handle is turned actuating the clamping screw 42, will engage the 50 gable of the building 10 in a secure manner without digging into the wood. As can be readily seen, the screw 34 in engagement with the nut 38 provides ready means for attaching a ground line to the antenna.

55 Referring now to the form of the invention as

shown in Figure 5 it will be seen that the generally L-shaped supporting member 60 of this form of the invention also embodies a vertical leg designated by reference numeral 62 with the arm 66 extending at a convenient angle thereto. A 5 clamping or jack screw 68 is likewise provided with a handle 70 and has the swivelled angle plate 72 pivotally mounted relative thereto. However, the angle plate 72 is provided with a substantially horizontal flange portion 74 and a substantially vertically extending flange portion 76 through which apertures 78 can be drilled for use in enabling screws 80 to be emplaced and engaged in the side of the building when the building is not provided with an overhanging peak. However, it is quite possible to permit the angle plate to become inserted under a shingle or the like thus eliminating the need of the screws 80. Obviously the form of the invention as indicated at 62 is provided with a U-shaped member 82 so that proper 10 clamping relationship between the jack screw 68 and the U-shaped member 82 may be had.

Proper care should be given to the mechanical stability of the antenna and its support. Where located on the roofs of buildings the antenna and supporting guys, if any, should not be located so as to interfere with operations of the fire department or where liable to cross with electrical lines. In the instant installation no guy wires are obviously necessary and since the vertical leg of the L-shaped member is relatively long it provides a satisfactory foundational base and stabilizer for the portion of the antenna mast which lies alongside it, as is evident. Also, the two spaced apart rings or collars make it possible to attach the mast on the ground before the over-all mount is carried to its place of installation or, it is permissible to simply pass the mast up through the rings or collars after the bracket means is anchored and this saves time in the installation steps, as will be clear to persons skilled in the art to which the invention relates. The three-point contact feature is important and when the jack screw is tightened up the complementary portions are under tension and effective clamping results are virtually assured.

Since from the foregoing the construction and advantages of this antenna bracket are readily apparent, further description is believed to be unnecessary.

However, since numerous modifications will readily occur to those skilled in the art after a consideration of the foregoing specification and accompanying drawings, it is not intended to limit the invention to the precise embodiments shown and described, but all suitable modifications and equivalents may be readily resorted to which fall within the scope of the appended claims.

Having described the invention, what is claimed as new is:

1. For use on an overhanging peak at either end of a gable roof or equivalent pitch roof construction, means for supporting the pole of an antenna directly from said roof, instead of on a chimney, as usual, said means comprising a substantially L-shaped member embodying a vertical long leg and a horizontal short leg, a horizontally disposed substantially U-shaped ridge saddle embodying a bight portion and arm portions, said arm portions being at right angles to said long leg and adapted to straddle and rest firmly against the inclined portions of the roof on opposite sides of the ridge of said roof, said bight portion being secured intermediate its ends to 75

the upper end portion of said long leg, anti-slipping members mounted on the free end portions of said arms and adapted to rest against coacting portions of said roof, nut means rigidly secured to the free end of the short leg, a jack screw threaded through said nut means and having a handle at one end and an angle iron plate at the opposite end, said plate being adjustably mounted on said jack screw, and pole embracing rings mounted at vertically spaced points on said long leg and provided with set screws.

2. The structure specified in claim 1, wherein said arms are of corresponding lengths and of lengths greater than the relatively shorter short leg, said short leg being spaced downwardly from said arms, being in a plane parallel with said arms and occupying a position which is directly beneath the space at the center of said arms.

3. For use on the peak at either end of a gable roof on a building, clamp means whereby a television antenna may be attached and supported wholly and directly from the selected peak comprising a rigid support member embodying an elongated vertical leg adapted to be disposed in spaced parallelism in respect to an end of the wall of said building, a horizontal leg joined with said vertical leg and adapted to extend at right angles from said vertical leg and to underlie the overhanging roof peak, horizontally disposed yoke means carried by the upper end of said vertical leg, said yoke means being U-shaped in plan and having a pair of independent spaced parallel arm portions adapted to straddle the ridge of the roof with the ridge projecting through the space between said arm portions, an end thrust and clamping plate, a jack screw swivelly connected with said plate, screw-threaded means operatively and adjustably mounting said jack screw on said horizontal leg, and means mounted on said vertical leg for the attachment thereto of an antenna mast.

4. For use on the peak at either end of a gable roof, clamp means whereby a television antenna may be attached and supported wholly and directly from the selected peak comprising a rigid support member embodying an elongated vertical leg adapted to be disposed in spaced parallelism in respect to an end of the wall of a building, a horizontal leg joined with said vertical leg and adapted to extend at right angles from said vertical leg and to underlie the overhanging roof peak, horizontally disposed U-shaped means integrated with the upper end of said vertical leg and having spaced parallel arm portions adapted to straddle the ridge of the roof, and an end thrust and clamping plate, a jack screw swivelly connected with said plate, a screw-threaded means operatively and adjustably mounting said jack screw on said horizontal leg, said clamping plate being of angular form, said jack screw being provided with handle means, vertically spaced mast-embracing rings carried by said vertical leg and adapted to receive and encircle said mast.
